UNITED STATES PATENT OFFICE.

MAJOR J. LOWENSTEIN, OF ST. LOUIS, MISSOURI.

DESIGN FOR A BLANK FOR OFFICIAL-AWARD RIBBONS AND DECLARATIONS.

SPECIFICATION forming part of Design No. 37,259, dated December 13, 1904.

Application filed October 26, 1904. Serial No. 230,150. Term of patent 3½ years.

To all whom it may concern:

Be it known that I, MAJOR J. LOWENSTEIN, a citizen of the United States, and a resident of St. Louis, Missouri, have invented a new, original, and ornamental Design for a Blank for Official-Award Ribbons and Declarations, of which the following is a specification, reference being had to the accompanying drawings, forming a part hereof.

Figure 1 is a plan view of a blank for an official-award ribbon and declaration, showing

my new design. Fig. 2 is an edge view of the same.

What I claim as new, and desire to secure by Letters Patent, is—

The ornamental design for a blank for an official - award ribbon and declaration, as shown.

MAJOR J. LOWENSTEIN.
